US00D924828S

(12) **United States Design Patent** (10) **Patent No.:** **US D924,828 S**
(45) **Date of Patent:** **** Jul. 13, 2021**

(54) **ELECTRONIC DEVICE**

(71) Applicant: **SAMSUNG ELECTRONICS CO., LTD.**, Suwon-si (KR)

(72) Inventors: **Wonseok Oh**, Suwon-si (KR); **Keemoon Lee**, Suwon-si (KR)

(73) Assignee: **SAMSUNG ELECTRONICS CO., LTD.**, Gyeonggi-Do (KR)

(**) Term: **15 Years**

(21) Appl. No.: **29/705,312**

(22) Filed: **Sep. 11, 2019**

(30) **Foreign Application Priority Data**

Jul. 23, 2019 (KR) 30-2019-0035231

(51) **LOC (13) Cl.** **14-03**

CLAIM

The ornamental design for an electronic device, as shown and described.

DESCRIPTION

FIG. 1 is a front perspective view of an electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines illustrating portions of the electronic device form no part of the claimed design.

1 Claim, 6 Drawing Sheets
